UNITED STATES PATENT OFFICE

SALVATORE SEDITA, OF BUFFALO, NEW YORK.

WASHING MACHINE.

Application filed July 12, 1927. Serial No. 205,139.

This invention relates to a washing machine which is more particularly designed for domestic use in washing clothes and the like.

5 It is the object of this invention to provide a machine of this character which permits of performing the operations of washing the clothes, wringing out the excess moisture therein after the washing operation and then drying the same by means of an air current while the clothes remain in the same machine, thereby simplifying the operating of cleaning clothes and reducing the amount of labor which otherwise would be 10 necessary for repeatedly handling the same.

In the accompanying drawings:

Figure 1 is a vertical section of a washing machine embodying an improved form of my invention, the parts being shown in a 20 position in which the same perform the operation of washing clothes and the like and also showing the clothes lifter in its elevated position.

Figure 2 is a fragmentary view similar to Fig. 1 but showing the clothes lifter in its depressed position.

Figure 3 is a top plan view of the machine.

Figures 4, 5 and 6 are horizontal sections taken on the correspondingly numbered lines 30 in Fig. 1.

Figures 7 and 8 are fragmentary views similar to Fig. 6 but showing the parts in different positions.

Figure 9 is a fragmentary sectional view 35 similar to Figs. 1 and 2 but showing the parts in the position which they occupy when the machine is used for wringing or squeezing the bulk of the moisture or water out of the clothes preparatory to air drying 40 the same.

Figure 10 is a fragmentary vertical section taken on line 10—10 Fig. 2.

Figure 11 is a fragmentary vertical section similar to Figs. 1, 2 and 9 but showing 45 the parts organized for air-drying the clothes after the free water or moisture has been pressed out of the same.

Figure 12 is a fragmentary vertical section taken on line 12—12 Fig. 11.

50 Figure 13 is a fragmentary vertical section showing the draining cock on the water tub or tank whereby the water may be emptied from the tub when desired.

Similar characters of reference indicate

like parts in the several figures of the drawings:

The numeral 20 represents a plurality of legs which are united at their upper ends to a central block 21 and form therewith the main parts of the frame which support the 60 working elements of the machine. On top of this frame is mounted a tub or tank which is adapted to contain the clothes or other materials which have to be washed, this tub in its preferred form consisting of a bottom 65 22 secured to the top of the frame and an upright cylindrical wall 23 extending upwardly from the bottom and a cover 24 which is removably seated on the upper edge of the wall. Within the lower part of the 70 tub is arranged a vertically movable lifter 25 which preferably has the form of a lifting disk which is provided with a plurality of perforations 26. Vertical motion may be imparted to this lifting disk by various 75 means, those shown in the drawings being satisfactory and consisting of an upright lifting or shifting rod 27 which is preferably 80 hollow for a purpose which is presently to appear and which extends through the 85 bottom of the tub and is guided in the frame block 21 in such manner that this rod can be raised and lowered but is incapable of turning, this being preferably accomplished by making this rod square in cross-section, 90 as shown in Fig. 5, and engaging the same with an opening 28 of corresponding form in the guide block 21. The lifting disk 25 is secured to the upper part of this lifting rod in any suitable manner and the raising 95 and lowering of the same is effected by means which include two crank wheels 29 arranged on opposite sides of the lower part of the lifting rod and each provided with a crank 30, and a pitman 31 connecting each 95 crank pin 30 with a cross-piece 32 on the lower end of the lifting rod. Upon rotating the crank wheels 29 the crank connection of the same with the lifting rod will cause the latter to rise and fall and thereby raise and 100 lower the lifting disk 25 in the tub, together with any clothes or other material resting thereon. The two crank wheels 29 are preferably constructed in the form of gear wheels and the same are caused to turn in 105 unison by means of two driving pinions 33 meshing therewith and mounted on a countershaft 34 which is journaled horizon-

tally on the lower part of the main frame vertically in line with the axis of the lifting rod 27.

Although motion for operating the shaft 5 34 may be derived from any suitable prime mover it is preferable to employ for this purpose a water motor, the casing 35 of which is mounted on the main frame and receives water under pressure through a 10 supply pipe 36, which water is directed against rotary blades 37 within the casing for the purpose of turning the driving shaft 38 of this motor. Motion in the present case may be transmitted from this motor to the driven 15 shaft 34 by an intermediate transmission mechanism of any suitable construction, which transmission mechanism however preferably comprises an intermediate shaft 39 journaled in suitable bearings on the 20 main frame, a belt 40 passing around driving and driven pulleys 41—42 on the motor shaft 38 and the intermediate shaft 39, a belt 43 passing around pulleys 44 and 45 on the shafts 39 and 34, and a clutch for connecting and disconnecting the pulleys 42, 44 and consisting of a clutch jaw 46 arranged on the pulley 42 and a clutch jaw 47 splined on the shaft 39 and movable into and out of engagement with the clutch jaw 46 by means 30 of a shifter rod 48 extending to the side of the machine where the same is conveniently accessible to the operator of the machine, as best shown in Fig. 6. By means of this organization the motor may be coupled with 35 or uncoupled from the driven shaft 34 for operating the parts connected with the latter or arresting the operation of the same to suit the particular function which the machine is to perform.

40 The tub or tank is adapted to be filled about one-third full of water and the clothes 49 or other articles to be washed are placed on top the lifting disk so that when the latter is raised and lowered by means of the 45 crank mechanism these articles are soaped in the water so that the dirt therein is loosened and removed therefrom by the water. This soiled water after the operation of cleaning has been completed may be removed from 50 the tub by means of a drain cock 50 arranged on the side wall of the tank at the lower end thereof, as shown in Fig. 13.

After the articles to be washed are raised and lowered the upper side of the mass of 55 articles is pressed against the underside of a head 51 arranged in the upper part of the tub, so that these articles are subjected to a squeezing operation. In the preferred construction this head which serves as an abutment is yieldingly supported so as to adapt 60 the same to variations in the mass of articles which are to be washed, and this head is also oscillated about a vertical axis so that a rubbing effect is exerted upon the articles 65 and the same are also tumbled about more or

less so that all parts of the mass of articles are subjected to the cleaning operation of the machine. In the preferred construction this upper head 51 has the form of a horizontal disk and the same is provided at its 70 margin edge with an upwardly extending flange 52 arranged close to the wall of the tub and on its underside this head is provided with a plurality of cleats 53 which enable this head to obtain a better grip on the 75 articles to be washed for the purpose of rubbing and agitating the same. The central part of the head 51 is mounted on the upper end of an upright rock shaft 54 so as to be compelled to turn therewith but 80 capable of sliding vertically thereon and also capable of being wholly detached therefrom when required, and also yielding vertically when subjected to the upward pressure of the lifting disk 25 through the medium of a mass of articles arranged between the same.

The preferred means for thus mounting the head on the rock shaft which is shown in the drawings consist of a horizontal supporting disk 55 arranged within the flange 52 of the head and provided at its center with a square opening 56 which engages with the square upper end 57 of the rock shaft 54, a cotter pin 58 passing through the square 90 end of this shaft above the supporting disk 55, a plurality of upright coupling bolts 59 connected at their lower ends with the rubbing disk 51 and passing at their upper ends through the supporting disk 55 and a plurality of cushion springs 60 each of which surrounds one of the coupling bolts 59 and is interposed between the rubbing head 51 and the supporting disk 55, as shown in Figs. 1, 2, and 9.

105 After the lifting disk 25 is raised, the articles 49 to be washed are pressed against the underside of the rubbing head 51 and when this pressure exceeds the tension of the springs 60 the latter yield as much as 110 is necessary in order to prevent the machine from becoming bound or any of its parts broken, and thereby permitting the machine to automatically adapt itself to bundles or masses of articles to be washed which may 115 vary in size, without altering the effectiveness in the cleaning operation.

The rocking motion of the shaft 54 together with the rubbing head 51 is preferably effected by the mechanism which is 120 shown in the drawings and which consists of two horn-shaped rock arms 61, 62 arranged on diametrically opposite sides of the lower end of the rock shaft 54, and two horn-shaped tappets 63, 64 arranged on diametrically opposite sides of the driven shaft 34 and adapted to engage alternately with the rock arms 61, 62. As shown in Fig. 6, the tappet 63 has shifted the rock arm 61 as far as possible and is about to clear the 125 130

same, whereby the turning movement of the rock shaft 54 in this direction is arrested. As the driven shaft 34 continues its rotation, the other tappet 64 now engages with 5 the companion rock arm 62 and turns the same in the opposite direction together with the rock shaft 54 and the parts associated therewith, this reversely turning operation being shown in nearly its completed form in 10 Fig. 7 and in its entirely completed form in Fig. 8. The parts are now in position to be again rocked in the reverse direction by engagement with the tappet 63 with the companion rock arm 61. This mechanism 15 results in converting the rotary motion of the driven shaft 34 into an oscillating motion of the rock shaft 54 so that this rocking action will extend through 180 degrees, thereby causing the rubbing head 51 to operate very effectively by means of its cleats 20 53 on all the articles which are placed in the machine.

Inasmuch as the driven shaft 34 is operatively connected with the crank mechanism which reciprocates the lifting disk 25 vertically and also the tappet mechanism which produces an oscillating movement of the rubbing head 51, it follows that the 30 operations of raising and lowering the mass of articles and also horizontally rubbing or agitating the same takes place simultaneously, thereby subjecting the articles to a very effective cleaning operation. It will also be evident that by reason of this organization 35 the opening and closing of the clutch jaws 46 and 47 will cause this vertical agitating and horizontal rubbing action to start and stop in unison.

After a batch of clothes or other articles 40 have been thus washed a sufficient length of time to remove the dirt therefrom the mass of articles is lifted bodily out of the water and pressed against the underside of the rubbing head so as to squeeze out the excess 45 or free water contained therein, this operation taking place while the clutch 46, 47 is open and the disk 25 and the rubbing head 51 are not subjected to the effects of any power mechanism. This operation of 50 wringing out or removing the free moisture from the articles is preferably effected by manually actuated means and in their preferred construction these means are constructed as follows.—

Arranged on opposite sides of the tank are two lifting yokes each of which is preferably constructed in the form of a letter U and provided with inner and outer legs 65, 66 which straddle the wall of the tub 60 and are guided thereon by means of a loop 67 arranged on the outer side of this wall and embracing the outer leg 66, a foot 68 arranged at the lower edge of each inner leg 65 and adapted to engage with the underside of the adjacent part of the lifting disk 65

25, a gear rack 69 arranged on the outer leg 66 of each lifting yoke, a gear pinion 70 meshing with each of these gear racks, a horizontal shaft 71 journaled in suitable bearings on the underside of the tub and carrying the gear pinions 70 and provided at one end with a square surface 72 which is adapted to receive a hand crank 73, and a detent pawl or disk 74 mounted on the wall of the tub and adapted to engage with the 75 adjacent lifting pinion 70 for preventing turning of the same in the direction which permits of lowering the lifting yokes.

During the washing operation the lifting yokes are arranged in their lowermost position in which the lifting feet 68 are arranged sufficiently far below the underside of the lifting disk 25 so that the latter is free to rise and fall for effecting the washing operation without interfering with the 80 lifting feet, the latter being shown in this lowermost or inoperative position in Figs. 1 and 2. When it is desired to wring or squeeze the excess water out of the clothes or other articles the shaft 71 is turned by 85 means of a hand crank 73 in the proper direction for causing the lifting feet 68 to engage the underside of the lifting disk 25 and raise the latter together with the mass of material thereon out of the water and 90 press the same firmly against the underside of the rubbing disk 51, as shown in Fig. 9, whereby the water is squeezed out of the articles and caused to run back into the lower part of the tank or tub. The lifting 95 disk together with the yokes may be held in this elevated position by engaging the detent pawl 74 with one of the lifting pins 70, as shown in Fig. 10. While elevating the lifting disk at this time the same is 100 moved independently of the power driven mechanism which agitates the same vertically during the cleaning operation. In order to permit of this the lifting disk is connected with the hollow lifting shaft 71 105 in such manner that these parts are compelled to turn together but the lifting disk is free to move vertically independently of the lifting rod 27. This is preferably accomplished by providing the central part of 110 the lifting disk with a square opening 75 which receives the square upper part of the hollow shaft 27, as shown in Fig. 5. The downward movement of the lifting disk 25 on the lifting rod 27 is however limited by 115 means of a stop collar 76 on this rod which is adapted to engage with the underside of this disk for raising the latter, as shown in Fig. 1.

After the excess water has been wrung out 120 of the mass of articles in the manner described and the latter are in a damp condition the same are now subjected to means which supply air under pressure so that the articles are aerated and the drying of the 125 130

same is completed. In order to do this the rubbing head 51 is first removed from the upper end of the rock shaft 54 which can be readily done after taking off the cover and 5 withdrawing the cotter pin 58. After such removal of the rubbing disk the cover is again restored thereby forming a free space within the upper part of the tub in which the mass of material which has been washed is 10 free to expand while being subjected to streams of air under pressure for drying the same, as shown in Fig. 11. This air is delivered against the underside of the mass of clothes, preferably on opposite sides of 15 the center of the axis of rotation by means of two delivery nozzles 77 mounted on the underside of the lifting disk 25 and each provided at its upper end with an air outlet 78 which delivers the air under pressure against 20 the underside of the mass of articles. Each of these air delivery nozzles 77 has an inlet 79 which is adapted to register with the outlet 80 of an air supply pipe or conduit 81, which outlet 80 is so located on the wall 22 25 of the tub that when the lifting disk 25 has been raised to its highest position by the manually operated wringing mechanism then this air outlet 80 of the supply conduit 81 will register with the air inlet 79 of the 30 respective nozzle, as shown in Fig. 12. For the purpose of obtaining an effective joint between the air supply pipe and the delivery nozzle a coupling tube 82 is employed which is slidably mounted in the outlet 80 and 35 adapted to be engaged with and disengaged from the inlet of the respective delivery nozzle 77. As shown by full lines in Fig. 12 this coupling tube is pushed inwardly so as to connect the air supply pipe 81 with 40 the nozzle 77, this being the position of the parts when the machine is used for drying the clothes by means of air currents. When however, the machine is being used for washing and wringing them the coupling tube 45 82 is withdrawn from the nozzle 77 as shown by dotted lines in Fig. 12 so that the lifting disk 25 is free to rise and fall independently of the air supply mechanism.

The air for thus drying the clothes is supplied by means of a blower, the casing 83 of which is connected by means of a main pipe 84 with the two distributing conduits 81 leading to the respective delivery nozzle 77. This blower case is mounted on a suitable part of the main frame and the shaft 85 of its air impeller is rotated by means of a belt 86 passing around pulleys 87 and 88 arranged respectively on the shafts 39 and 85. The pulley 87 may be connected with and 50 connected from the shaft 39 by a clutch which may consist of a driven clutch jaw 89 arranged on the driving pulley 87, a driving clutch jaw 90 splined on the shaft 39, and a 55 shipper rod 91 which is operatively connected with the splined clutch jaw 90 and

extends to the side of the machine where the operator may conveniently manipulate the parts for opening and closing the clutch jaws 89, 90 as desired.

In the operation of this machine the air 70 pressure supplying means are rendered inoperative while the washing and wringing operations are in use, and vice-versa, this being possible by proper manipulation of the clutch jaws 46 and 47 which control the 75 washing and wringing mechanism and the clutch jaws 89, 90 which control the drying mechanism.

During the washing operation each of the air delivery nozzles 77 becomes filled with 80 water and it is therefore necessary or at least desirable to permit this water to drain out each of these nozzles before beginning the operation. This is preferably accomplished by means of an air pressure controlled check valve which in the present case consists of a valve gate 92 pivoted at its upper end by a hinge 93 to the top of the nozzle 77 so that the same is free to swing toward and from a drain opening 94 in the nozzle, and a spring 95 connecting this valve gate with the nozzle 90 so as to hold the same yieldingly in its open position during the washing and wringing operation as shown by dotted lines in Fig. 12. When thus open, this check valve 92 permits the water to freely enter each nozzle 77 and escape therefrom and when the nozzles are raised together with the lifting disk 25 for the purpose of wringing out the water from the articles which are being washed, then the outlet opening 94 will be open so as to permit the air nozzle 77 to be emptied of any water which may be therein. When, however, the air pressure from the blower is delivered into the nozzle 77 this pressure 105 operates to close the valve gates 92 by overcoming the resistance of the springs 95 so that thereafter all the air supplied by the blower will be directed against the underside of the mass of clothes or other articles 110 and thereby utilize the same most effectively for drying these articles. The air under pressure is delivered in this manner against the underside of the mass of articles 115 a sufficient length of time to cause the air to thoroughly permeate the entire mass and completely dry the same and thus avoid the necessity of hanging the clothes out on a line for this purpose. These dried articles may then be removed by taking off the cover 120 24. In order to permit the moisture-laden air to escape from the tub, the central part of the cover is provided with air escape openings 96 which openings are preferably formed in the handle 27 of the cover which extends over an air outlet tube 98 in the center of the cover.

For convenience in manipulating the rubbing disk 51 and associated parts the central part of the supporting disk 55 is provided 130

with a handle 99 which is preferably foldable so that the same can be turned down against the top of the supporting disk 55, as shown in Figs. 1 and 4, and therefore be out of the way when not in use.

It will now be apparent that this machine permits of easily and conveniently performing the operations of washing, rinsing and wringing a mass of articles and then subsequently drying the same in the machine so that the articles to be washed only require one insertion in the machine and one removal thereby facilitating this work and minimizing the labor connected therewith.

15 I claim as my invention:—

1. A washing machine comprising a tub adapted to contain water and the clothes to be washed, a vertically reciprocating lifter arranged in the lower part of the tub and adapted to raise and lower the clothes, a head which is arranged in the upper part of the tub and against which the clothes are adapted to be pressed by the lifter, and means for oscillating said head about a vertical axis including an upright rock shaft connected at its upper end with said head and provided at its lower end with two rock arms projecting from diametrically opposite sides thereof, and a rotary shaft arranged horizontally below said upright shaft and provided on its diametrically opposite sides with tappets adapted to engage alternately with the rock arms of said upright shaft.

2. A washing machine comprising a tub adapted to contain water and the clothes to be washed, a vertically reciprocating lifter arranged in the lower part of the tub and adapted to raise and lower the clothes, a head which is arranged in the upper part of the tub and against which the clothes are adapted to be pressed by the lifter, means for actuating said lifter including a hollow upright lifting rod connected at its upper end with said lifter and slidable vertically in the bottom of said tub but held against turning therein, and means for actuating said head including an upright rock shaft arranged in said hollow lifting rod and connected at its upper end with said head.

3. A washing machine comprising a tub adapted to contain water and the clothes to be washed, a vertically reciprocating lifting disk arranged in the lower part of the tub and adapted to raise the clothes, a rubbing head against which the clothes are pressed by said lifting disk and which oscillates about a vertical axis, and means for raising said lifting disk to raise the clothes out of the water and press them against the rubbing head after the washing operation, including a U-shaped lifting yoke the legs of which straddle the wall of the tub, a foot arranged on the inner leg of said yoke and adapted to engage the underside of said lifting disk, a gear rack arranged on the outer

leg of said yoke and a gear pinion meshing with said rack.

4. A washing machine comprising a tub adapted to contain water and the clothes to be washed, a vertically reciprocating lifting disk arranged in the lower part of the tub and adapted to raise the clothes, a rubbing head against which the clothes are pressed by said lifting disk and which oscillates about a vertical axis, and means for raising said lifting disk to raise the clothes out of the water and press them against the rubbing head after the washing operation, including a U-shaped lifting yoke the legs of which straddle the wall of the tub, a foot arranged on the inner leg of said yoke and adapted to engage the underside of said lifting disk, a gear rack arranged on the outer leg of said yoke, a gear pinion meshing with said rack, a shaft carrying said gear pinions, and a detent pawl adapted to engage said pinion.

5. A washing machine comprising a tub adapted to contain water and the clothes to be washed, a head arranged in the upper part of the tub, a lifting disk arranged in the lower part of the tub and adapted to press the clothes against said head, and means for delivering air against the clothes including a nozzle arranged on the lifting disk and having an upwardly directed air outlet, and means for supplying air under pressure to said nozzle.

6. A washing machine comprising a tub adapted to contain water and the clothes to be washed, a head arranged in the upper part of the tub, a lifting disk arranged in the lower part of the tub and adapted to press the clothes against said head, and means for delivering air against the clothes including a nozzle arranged on the lifting disk and having an upwardly directed air outlet, means for supplying air under pressure to said nozzle including a blower casing having an outlet, and a conduit connected with said outlet and having an outlet adapted to register with said nozzle in the elevated position of the same.

7. A washing machine comprising a tub adapted to contain water and the clothes to be washed, a head arranged in the upper part of the tub, a lifting disk arranged in the lower part of the tub and adapted to press the clothes against said head, and means for delivering air against the clothes including a nozzle arranged on the lifting disk and having an upwardly directed air outlet, means for supplying air under pressure to said nozzle including a blower casing having an outlet, a conduit connected with said outlet and having an outlet adapted to register with said nozzle in the elevated position of the same and a coupling tube for connecting and disconnecting said conduit and nozzle.

8. A washing machine comprising a tub adapted to contain water and the clothes to be washed, a head arranged in the upper part of the tub, a lifting disk arranged in the lower part of the tub and adapted to press the clothes against said head, and means for delivering air against the clothes including a nozzle arranged on the lifting

disk and having an upwardly directed air outlet, means for supplying air under pressure to said nozzle, and a check valve for permitting water to escape from said nozzle but closing under air pressure. ¹⁰

In testimony whereof I hereby affix my signature.

SALVATORE SEDITA.
